Primary Examiner — T Chase Nelson*Assistant Examiner* — Rachel Wolfe(74) *Attorney, Agent, or Firm* — Jose Cherson Weissbrot(57) **CLAIM**

The ornamental design for a wall lamp, as shown and described.

DESCRIPTION

FIG. 1 is a front, left, top perspective view of a wall lamp, showing my new design;

FIG. 2 is a rear, left, bottom perspective view thereof;

FIG. 3 is a front elevational view of the enlarged scale thereof;

FIG. 4 is a rear elevational view of the enlarged scale thereof;

FIG. 5 is a left side elevational view of the reduced scale thereof;

FIG. 6 is a right side elevational view of the reduced scale thereof;

FIG. 7 is a top plan view of the reduced scale thereof;

FIG. 8 is a bottom plan view of the reduced scale thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2;

FIG. 12 is an enlarged view of detail 12 in FIG. 2;

FIG. 13 is an enlarged view of detail 13 in FIG. 5; and,

FIG. 14 is an enlarged view of detail 14 in FIG. 6.

The dashed broken lines in the figures are for the purposes of illustrating portions of the wall lamp and form no part of the claimed design.

The dash-dot-dash broken lines are for notating enlarged views and form no part of the claimed design.

1 Claim, 12 Drawing Sheets(56)
